UNITED STATES PATENT OFFICE.

JOHN SPRING, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 14,042, dated July 3, 1883.

Application filed March 16, 1883. Term of patent 3½ years.

To all whom it may concern:

Be it known that I, JOHN SPRING, of New York city, county and State of New York, have invented a new and original Design for 5 Carpets, of which the following is a specification.

This invention relates to a new and original design for carpets and similar fabrics; and it consists in the novel grouping and configuration of parts hereinafter more fully described.

The accompanying photograph illustrates a face view of a carpet having my new design.

A is a band, composed of the stripe a, having below the series of ornamented rectangles 15 d and b.

B is a band containing an ornamentation, e, resembling certain flowers and ornamentation k, resembling a spray of forget-me-nots, these figures being set alternately with leaf-like ornamentations f and l along the band.

D is a band containing a scalloped ornamentation above a zigzag ornamentation, g.

F is a stripe showing an ornamentation composed of a rectangular figure, I, having a flower, h, in its center, of a rectangular figure E, made up of four ornamental squares, each of

which has a leafy ornamentation upon it. Along the bottom of the stripe F is an ornamental pattern. One half of the figure E is shown at one side of the photograph and the other half on the other side. When the carpet is matched, the complete figure E will be formed by bringing these halves together.

I claim—

1. The design for carpets, consisting of the 35 band A, containing figures b d, substantially as shown.
2. The design for carpets, consisting of the figure B, substantially as shown.
3. The design for carpets, consisting of the 40 figure I, substantially as shown.
4. The design for carpets, consisting of the figure E, substantially as shown.
5. The design for carpets, consisting of the stripe F, containing figures I and E, substan- 45 tially as shown.
6. The design for a carpet, substantially as shown.
